UNITED STATES PATENT OFFICE.

WILLIAM VOLKHARDT, OF STAPLETON, NEW YORK.

TIE-PLATE.

1,290,428.

Specification of Letters Patent.

Patented Jan. 7, 1919.

Application filed September 12, 1917. Serial No. 190,970.

To all whom it may concern:

Be it known that I, WILLIAM VOLKHARDT, a citizen of the United States, residing at Stapleton, Richmond borough, New York, 5 in the county of New York and State of New York, have invented a new and useful Tie-Plate, of which the following is a specification.

This invention relates to plates of that 10 type adapted to be interposed between wooden railway ties and the rails resting thereon.

Heretofore it has been the practice to use flat plates for the purpose of distributing 15 the load over a more extensive surface on the tie than would be possible should the rails rest directly on the tie, thus to reduce the cutting and tearing of the tie. It has been found, however, that, due to the greatly 20 increased weight of modern railway equipment, these flat tie plates commonly used do not materially reduce the injury to the ties but, on the contrary, soon cut into and sometimes become embedded within the ties, 25 this cutting action being produced by the sharp angles formed at the ends of the plates.

It has also been the practice to form on 30 the upper face of a tie plate a transverse rib constituting an abutment for the outer base flange of the rail resting on the tie plate. Under present conditions the use of such use are being dispensed with owing to 35 the high cost of material and the desire to eliminate as much metal as possible in the construction of various articles.

One of the objects of the present invention is to provide a tie plate the ends of 40 which are so shaped that they will not dig into a wooden tie but, on the contrary, will merely compress the tie, thus preventing undesirable injury such as heretofore resulted from cutting the fibers of the tie.

45 A further object is to provide a tie plate utilizing, in lieu of an upstanding rib, up-struck ears constituting abutments for the outer base flange of the rail, the formation of these ears requiring no more metal than 50 would be necessary in the construction of a flat tie plate.

With the foregoing and other objects in view, which will appear as the description proceeds, the invention resides in the combination and arrangement of parts and in

the details of construction hereinafter described and claimed, it being understood that changes in the precise embodiment of the invention can be made within the scope of what is claimed, without departing from 60 the spirit of the invention.

In the accompanying drawings the preferred forms of the invention have been shown.

In said drawings:—

Figure 1 is a side elevation of a tie plate embodying the present improvements.

Fig. 2 is a plan view thereof.

Fig. 3 is a section on line 3—3 Fig. 2.

Fig. 4 is a section on line 4—4 Fig. 2.

Referring to the figures by characters of reference 1 designates a tie plate which can be made of any preferred material and of any desired dimensions. This tie plate is perfectly flat on both faces and, in the construction illustrated in Figs. 1 and 2 the ends of the plate are curved upwardly to a slight extent as indicated at 2 thus to present upwardly curved bearing faces 3 at the ends of the plate.

Projecting upwardly from the sides of the plate 1 near one end are ears 4 the inner sides of which constitute abutments or shoulders for engagement by the edge of the outer base flange of a rail. As shown in Figs. 1 to 4 inclusive these ears can be made by striking them upwardly from the plate so that they will diverge upwardly. See Fig. 3. If preferred, however, these ribs can be made by pressing the metal upwardly so that there will be no incisions at the sides of the ears.

Spike receiving apertures 5 are preferably formed in the plate 1 between the ears 4 and formed in the plate 1 along the center thereof and near the remote end is an elongated spike receiving opening 6.

In using the tie plate herein described the same is placed on a tie so as to extend longitudinally thereof. The rail is then placed on the plate between the openings 5 and 6 and with the outer base flange of the rail pressing laterally against the inner sides of the lugs 4. Spikes are then driven or screwed through the openings 5 so that the heads thereof will lap the outer base flange of the rail and another spike is driven or screwed through the opening 6 at a point where its head will engage the inner base flange of the rail. Obviously by providing 100 105 110

an elongated spike receiving opening 6, the plate can be used in connection with rails of different widths.

Although only three spike receiving openings have been shown it is to be understood that a greater number can be employed if desired. Also instead of providing angular spike receiving openings, oval or other shaped openings can be used. These changes are so obvious that it is not deemed necessary to illustrate them in detail.

Instead of providing a smooth bottom surface, said surface can be roughened in any desired manner, as by providing corrugations or the like.

What is claimed is:—

1. A tie plate having its end portions curved upwardly and outwardly to present curved thrust bearings diverging throughout their lengths.

2. A tie plate of uniform thickness and having a flat upper face, the ends of the plate being curved upwardly and outwardly to present rounded end thrust bearings diverging throughout their lengths.

3. A tie plate having side lugs projecting upwardly therefrom along upwardly diverging lines and separated at their sides and one end from the plate, the inner sides of the lugs throughout their lengths constituting abutments for the outer base flange of a rail and their outer sides contacting throughout their lengths with and backed by

walls of the openings in the plate from which the respective lugs are projected. 35

4. A tie plate having upthrust lugs at the sides thereof diverging upwardly and separated at their sides and one end from the plate, the inner sides of the lugs throughout their lengths constituting side thrust bearings for the outer base flange of a rail and the outer sides of the lugs being backed throughout their lengths by the outer walls of the openings under the lugs and in the plate. 40 45

5. A tie plate having side lugs projecting upwardly therefrom along upwardly diverging lines, the sides and one end of each lug being separated from the plate and the inner sides of the lugs constituting abutments for the outer base flange of a rail while the outer sides of the lugs are in contact throughout their lengths with the outer walls of the openings in the tie plate from which the lugs are projected, the ends of said plate having their bottom faces curved upwardly and outwardly from the top to the bottom to constitute end thrust bearings. 50 55

In testimony that I claim the foregoing as my own, I have hereto affixed my signature 60 in the presence of two witnesses.

WILLIAM VOLKHARDT.
